His Attorneys.

Patented Oct. 4, 1927.

UNITED STATES PATENT OFFICE.

HOWARD L. BEACH, OF PITTSBURGH, PENNSYLVANIA, ASSIGNOR TO CLARK CAR COMPANY, OF PITTSBURGH, PENNSYLVANIA, A CORPORATION OF NEW JERSEY.

LATCH-RELEASE MECHANISM.

Application filed February 26, 1923. Serial No. 621,158.

This invention relates to tilting side dump cars and more particularly to improvements in the device for locking the latch mechanism.

5 An object of this invention is to simplify the locking and operation of the device.

A further object of the invention is to provide means in a mechanism of the character described for definitely showing the position of the latch control mechanism from 10 and on both sides of the car.

A still further object of this invention is to provide means for adjustment to compensate for variations in the manufacture of 15 the component parts of the device and wear of the movable parts in service.

These, as well as other objects which will readily appear to those skilled in this particular art, I attain by means of the construction described in the specification and 20 illustrated in the drawings accompanying and forming part of this application.

In the drawings, Figure 1 is a view partially in elevation and partially in section of 25 mechanism embodying this invention.

In this view, which is a view looking toward one end of the latch and latch release mechanisms, the latch mechanism is shown latched, while the latch release mechanism is 30 shown in such position that when air is applied to the latch release cylinder the latch mechanism on the left side of the view will be unlatched in order to allow the body of the car to be tilted downwardly toward the 35 right hand side of the view. Fig. 2 is a detail view in elevation looking toward the device of Fig. 1 from the left hand side and Fig. 3 is a detail view of a portion of the device.

40 The mechanism is mounted on the car underframe by being riveted or otherwise secured to the center sill channels 4 and 5 and cover plate 6.

It will be understood that a tilting body 45 of suitable type is mounted on the underframe and that the sides of the body comprise doors which, by means of toggle mechanism including toggle links 7 and 8 are normally held in closed position. The toggle mechanisms are pivotally connected to the underframe at points 9 and 10 by links 11 and 12, in a manner similar to that construction shown in Fig. 2 of Patent No. 1, 333,293, of March 9, 1920.

55 The construction is such that the toggle

mechanisms are normally locked so as to hold the body in upright position and are only unlocked when it is desired to tilt the body toward one or the other side to dump the load.

The locking or latching mechanism includes latches 13 and 14 fixedly mounted on squared portions of longitudinally extending shafts 15 and 16 respectively and are adapted to be alternately rotated to engage 60 or disengage pins 17 and 18 which respectively pivotally connect links 7 and 11 and links 8 and 12. Shafts 15 and 16 are journaled for rotation in the opposite outer ends of a bracket 19 which is rigidly secured to 65 the underframe. The engagement therefor of latches 13 or 14 with pins 17 and 18 securely locks the doors in closed position and the body therefor in upright position.

Depending levers 20 and 21 are respectively rigidly secured to shafts 15 and 16. A latch release cylinder 22 at one end is pivotally connected by means of pin 23 to the lower end of lever 20 while rod 24 attached to a piston not shown, but movable within 70 cylinder 22 is pivotally connected to the lower end of lever 21 by means of a pivot pin 25.

Two coil springs 26 located on opposite 75 sides of cylinder 22 at one end are connected by means of a pin 27 to lever 21 and at the other end, by means of spring adjusting links 28, are connected to a pin 29 carried by lever 20. The springs tend to yieldingly hold the latches 13 and 14 in the position 80 shown in Fig. 1, that is, in engagement with pins 17 and 18. By admission of air to cylinder 22, levers 20 and 21 will be forced apart and both latches 13 and 14 unhooked from pins 17 and 18 respectively. The 85 mechanism thus far disclosed corresponds substantially to the mechanism disclosed in Patent No. 1,417,794 of May 30, 1922.

A locking bracket 30 is rigidly connected to 90 and depends from the underframe. Within this bracket, a locking rod is journaled. This rod comprises end portions 31 and 32 having handle portions 33 and 34 respectively. Rod portions 31 and 32 at their inner ends are threaded into a tubular sleeve 105 35 and therein cottered so as to permanently and rigidly hold them in proper internal adjusted relation.

The ends of this tube abut against depending 110 portions of locking bracket 30 and end-

wise movement of the assembled locking rod is thereby prevented.

End 31 is provided with a lug or locking boss 36 while end 32 is provided with a like boss 37. Each of these bosses is more or less fan-shaped as shown in Fig. 3. Lever 20 is provided with an abutment or stop 38 while lever 21 is provided with a similar abutment or stop 39. When handle 34 of the locking rod is turned down as shown in Fig. 1, locking boss 37 lies in the path of movement of stop 39 of lever 21, while boss 36 of lever 31 is turned out of the path of movement of stop 38 of lever 20. This prevents lever 21 from being swung and therefore shaft 16 from being rotated. With the mechanism in the position shown in Fig. 1, when air is applied to cylinder 22, the cylinder will move away from pin 25 carried at the lower end of lever 21 and will swing lever 20 so as to rotate shaft 15 and unlock latch 13 from pin 17. When handle 34 is turned up to vertical position, handle 33 will move down, lock boss 36 will move down into the path of stop 38 and lug 37 will move up and out of the path of stop 39. When air is admitted to cylinder 22, lever 21 will move, actuated by means of the piston within said cylinder and shaft 16 will be rotated so as to unlock latch 14 from pin 18.

The fan shape construction of lugs 36 and 37 provides means whereby during the movement of the locking rod and therefore handles 33 and 34, lug 36 will move into the path of movement of stop 38 before lug 37 has passed out of the path of movement of stop 39. In other words, the construction of these lugs is such that a decided lap between them is provided which prevents any unstable and unsafe position of the latch mechanism whereby both latches might become unlatched at the same time.

A fin 40 projecting downwardly from locking bracket 30 serves as a stop for limiting the rotation of the locking rod. The central or sleeve portion 35 of the locking rod carries a weight 41 and a stop member 42. When handle 34 is turned down to the position shown in Fig. 1, weight 41 holds stop member 42 in contact with the back of fin 40 (as shown in Fig. 1) and maintains lug 37 in the path of movement of stop 39. When, however, handle 33 is turned downwardly, weight 41 will hold the other end of stop 42 (the end shown at the bottom in Fig. 3) in contact with the front face of fin 40 thereby maintaining lock 36 in the path of movement of stop 38.

As the distance between the stops 38 and 39 may vary in different cars, the ends 31 and 32 of the locking rod assembly are made adjustable so as to be moved in or out of sleeve 35 to take care of this. After securing proper adjustment the ends 31 and 32 are locked in adjusted position by means of

cotter pins 43 which extend through the shaft ends and through holes formed for that purpose in the sleeve 35.

It will be noticed that the force of cylinder 22 tending to swing levers 20 and 21 outwardly is resisted by lugs 36 and 37 in such a position on rods 31 and 32 as tend to bend these rods in an upward direction. Bearing 44 on lever 20 and bearing 45 on lever 21 are provided to resist this bending tendency and to maintain rod ends 31 and 32 in correct alignment at all times.

Having thus described my invention, what I claim is:

1. In a tilting side dump car, two normally latched mechanisms, common means for actuating both of said mechanisms and a device rotatable between two extreme positions and provided with overlapping locking elements whereby only one of said latch locking mechanisms may be released at a time.

2. In a tilting side dump car, two latch mechanisms, common means for actuating both latch mechanisms and a manually operable locking device provided with overlapping, locking elements whereby only one of said latch mechanisms may be released at a time.

3. In a tilting side dump car, two latch mechanisms, a horizontal manually operable rod provided with overlapping locking elements for selectively releasing one or the other of said latch mechanisms.

4. In a tilting side dump car, two latch mechanisms, common means for actuating said mechanisms, a manually operable locking rod provided with overlapping, locking elements for selectively releasing said latch mechanisms and means for adjusting the distance between said overlapping, locking elements.

5. In a tilting side dump car, the combination with two oppositely operating latch mechanisms and a common air motor for actuating the same, of a manually operable locking device provided with overlapping, locking elements for selectively locking and releasing said latch mechanism and means for visibly indicating the position of said locking device.

6. In a tilting side dump car, two latch mechanisms, means for operating said latch mechanisms and locking means movable between two positions and adapted to release one latch mechanism when in one position and to release the other latch mechanism when in the other position, said locking means being adapted to lock both latch mechanisms when in an intermediate position.

7. In a tilting side dump car, two latch mechanisms, means for operating said latch mechanisms, locking means movable between two positions and adapted to release one latch mechanism when in one position and

- to release the other latch mechanism when in the other position, said locking means being adapted to lock both latch mechanisms against operation when in an intermediate 5 position and means for indicating the position of said locking means from both sides of said car.
8. In a tilting side dump car, two latch mechanisms, an operating lever connected to each latch mechanism, means for operating said levers, a rod extending through and beyond said levers and means on said rod for locking said levers so as to permit the operation of only one of said levers at a 15 time.
9. In a tilting side dump car, two latch mechanisms, means for operating said latch mechanisms, a rotatable latch control device operable from either side of said car and provided with overlapping latch locking elements adapted to permit the operation of only one of said latch mechanisms at a time.
10. In a tilting side dump car, two latch mechanisms, an operating lever secured to each latch mechanism, means for operating said levers, a locking device extending through and beyond said levers and means on said levers for preventing the distortion of said locking device.
11. In a tilting side dump car, two latch mechanisms, an operating lever secured to each latch mechanism, means for operating said levers, a rotatable locking rod extending through and beyond said levers and means on said levers for preventing distortion of said locking rod.
12. In a tilting side dump car, two latch mechanisms, an operating lever connected to each latch mechanism, means for operating said levers, a manually operable rod extending through and beyond said levers, lugs on said rod cooperating with said levers so as to permit the operation of only one of said levers at a time and means for adjusting the 45 distance between said lugs.
13. In a tilting side dump car, two oppositely swinging latch devices each having a depending lever movable therewith, a motor for swinging said devices, a rotatable latch controlling device extending through and beyond said levers and means on said levers for preventing distortion of said latch controlling device during the operation of said motor.
14. In a tilting side dump car, two oppositely operating latch mechanisms, an air motor constructed and arranged so as to be capable of actuating both of said latch mechanisms, a manually rotatable device 50 operable from either side of the car and provided with overlapping locking elements for selectively locking one or the other of said mechanisms against operation and prevent- ing unlatching of either until one is locked against unlatching and means on said rotatable device for visibly indicating the condition of the latch mechanisms. 65
15. In a tilting side dump car, pivotally mounted latch mechanisms on opposite sides of the car and each having a depending lever associated and movable therewith, an air operated motor suspended by said levers for exerting an unlatching movement to said mechanisms, springs resisting the operation of said motor, a single rotatable rod extending through and beyond said levers and provided with overlapping stops for preventing unlatching of either latch mechanism until one is locked against unlatching and oppositely directed handles for manually 70 operating said rod and for indicating the condition of said latch mechanisms. 75
16. In a tilting side dump car, two normally latched mechanisms, means for unlatching the same and a manually operated locking device operable from either side of the car and provided with overlapping locking elements preventing the unlatching of either latch mechanism until one latch mechanism is locked. 80
17. In a tilting side dump car, two normally latched mechanisms, means for unlatching the same, a manually operated locking device operable from either side of the car provided with overlapping locking elements and provided with means for adjusting the distance between said locking elements. 85
18. In a tilting side dump car, two oppositely swinging latch devices each having a depending lever movable therewith, a motor for swinging said devices, a rotatable locking device extending through and beyond said levers and means on said levers for preventing distortion of said latch locking device during the operation of said motor. 90
19. In a tilting side dump car, pivotally mounted latch mechanisms on opposite sides of the car each having a depending lever associated and movable therewith, an air operated motor suspended by said levers for exerting an unlatching movement to said mechanisms, springs resisting the operation of said motor, a single rotatable rod extending through and beyond said levers and provided with overlapping stops for preventing unlatching of either latch mechanism until one is locked and oppositely directed handles for manually operating and for definitely showing the position of said single rotatable rod. 100
20. In a tilting side dump car, two oppositely operating latch mechanisms, an air motor constructed and arranged so as to be capable of actuating both of said latch mechanisms, a manually rotatable device 105 operable from either side of the car and provided with overlapping locking elements for selectively locking one or the other of said mechanisms against operation and prevent- 110
21. In a tilting side dump car, two oppositely operating latch mechanisms, an air motor constructed and arranged so as to be capable of actuating both of said latch mechanisms, a manually rotatable device 115 operable from either side of the car and provided with overlapping locking elements for selectively locking one or the other of said mechanisms against operation and prevent- 120

In testimony whereof, I have hereunto subscribed my name this 1st day of February, 1923.

HOWARD L. BEACH.
